U.S. Cl. D2—315

FIG. 1

FIG. 2

FIG. 3

FIG. 1 is a top plan view of a combined toe piece and tongue member for a shoe showing my new design, the bottom being substantially a mirror image thereto;

FIG. 2 is a right side elevational view thereof, the left side being substantially a mirror image thereto;

FIG. 3 is a front elevational view thereof.

The remaining portion of a shoe, to which our new design is applied, is shown in dot and dash lines, for purposes of background illustration.

We claim:

The ornamental design for a combined toe piece and tongue member for a shoe, as shown and described.
